PORTABLE DUPLICATOR

Arthur J. Heyer, Oak Park, and Francis K. Moore,
Chicago, Ill., assignor to The Heyer Corporation, Chicago, Ill., a corporation of Illinois

Application December 16, 1950, Serial No. 13,468

Term of patent 14 years

(Cl. D64—11)

To all whom it may concern:

Be it known that we, Arthur J. Heyer and Francis K. Moore, citizens of the United States and residents of Oak Park and Chicago, respectively, in the county of Cook and State of Illinois, have invented a new, original, and ornamental Design for a Portable Duplicator, of which the following is a specification, reference being had to the accompanying drawing, forming a part thereof.

Fig. 1 is a perspective view of a portable duplicator, showing my new design;

Fig. 2 is an elevational view of the duplicator, illustrating the side thereof not shown in Fig. 1;

Fig. 3 is an end elevational view, illustrating the end of the duplicator not appearing in Fig. 1; and

Fig. 4 is a bottom view of the duplicator.

We claim:

The ornamental design for a portable duplicator, substantially as shown.

ARTHUR J. HEYER.
FRANCIS K. MOORE.
